UNITED STATES PATENT OFFICE

HARRISON D. FLEGEL, OF RACINE, WISCONSIN, ASSIGNOR TO ARNOLD ELECTRIC COMPANY, OF RACINE, WISCONSIN, A CORPORATION OF WISCONSIN

ICE-CREAM DISHER

Application filed May 3, 1926. Serial No. 106,194.

My invention relates to ice cream dishers, and has for its particular object the provision of a disher which is simple in construction, is very rigid, which is easily operable and which may be economically manufactured.

A further object of my invention is to provide an improved means for fastening the scraper to the spindle.

10 A further object is to provide an improved means for actuating the scraper.

A further object is to provide an improved means for securing the handle to the disher frame.

15 A further object is to provide an improved frame construction.

A further object is to provide an improved resilient means for actuating the scraper on its return stroke.

20 A further object is to provide an improved means for removably mounting the spindle in the frame.

A further object is to provide an improved finger rest.

25 Other objects will appear from the following description, reference being had to the accompanying drawings, in which

Figure 1 is an elevation of my improved disher, part of the handle being shown in 30 section;

Figure 2 is a detailed sectional view showing the method of securing the frame to the wood-screw;

Figure 3 is a plan view of the disher;

35 Figure 4 is a transverse sectional view taken on the line 4-4 of Figure 1;

Figure 5 is a perspective view of the finger rest; and

Figure 6 is a sectional view taken on the 40 line 6-6 of Figure 3.

The ice cream disher of my invention comprises a bowl 11 which is secured to the arcuate flared ends 12 of the frame 13 by soldering, spot-welding, or in any other suitable manner. The frame 13 is U-shaped and is formed from a single metallic bar having a pair of flat legs terminating in curved flanges for securing the frame to the scoop. The end cross portion of the frame 45 13 is secured to a handle 14 made of wood or

other suitable material by means of a screw 15. The screw 15 passes through a washer 16 and a supporting bracket 17, and is riveted so as to rigidly hold these parts together, and its end is drilled as shown in Figure 2 to form a bearing 18 for the reduced end of the spindle 19. The other end of the spindle 19 is rotatable in a bearing 20 which is pivotally mounted between the side portions of the frame 13, the ends 55 of this bearing 20 having rivet heads formed thereon not only to maintain the bearing in proper position, but also to brace the side portions of the frame 13. The scraper blade 22 has a trunnion 23 formed at its outer end, the trunnion freely fitting in a hole 24 formed in the bowl.

In the past, considerable difficulty has been encountered in securing the inner end 60 of the scraper blade to the end of the spindle. When hard ice cream is being dished, there is a considerable sheering strain on this connection and in the past the scrapers have frequently sheered off adjacent the spindle. I have overcome this 65 difficulty by providing the novel means for fastening the blade to the end of the spindle which is shown in detail in Fig. 6. A tongue 25, rectangular in cross-section, extends from the end of the spindle 19 and passes through a rectangular slot formed in the end of the scraper 22. A retaining member 26 made of copper or other suitable ductile metal having a similar slot is then 70 pressed over the tongue 25 and bent so as 75 to engage the sides of the scraper blade and also the surface of the spindle 19. The end of the tongue is riveted over this retaining member. The retaining member not only 80 holds the scraper to the spindle but also 85 reinforces the portion of the scraper lying adjacent the spindle.

A pinion 27 is pinned or otherwise suitably fixed to the end of the spindle 19 adjacent the handle and co-operates with a segment 28 formed integral with the lever 29. The lever 29 has a sleeve 30 fixed thereto or integral therewith, which is 90 rotatable on a pin 31 secured at the end of the bracket 17 by a nut 33. A cup-shaped 95 100

protecting housing 34 is riveted at the other end of the pin 31 and the edge surface adjacent the segment 28 guides and maintains the segment in its proper operating plane. A torsional helical spring 35 has one end 36 hooked through a notch formed in the lower edge of the housing, the other end 37 being hooked into a notch 38 at the upper end of the sleeve 30. A stop 39 integral with the segment 28 is adapted to arrest the segment in its normal position, the spring 35 being wound so as to tend to normally hold the stop 39 in engagement with the side of the frame 13. The operating stroke is limited by the abutting of the lever 29 with the frame 13.

As best shown in Fig. 1, I provide a means for resting the fingers of the hand when operating the disher by means of the thumb. This finger rest consists of a plate 41 having a hole 42 formed therein. The plate also has a pin 43 riveted thereto, the pin extending parallel and adjacent to the handle 14. This finger piece not only provides a rest for the fingers in the dishing operation, but the plate 41 provides a surface against which pressure can be brought to bear in the scooping operation. The position of the finger pin 43 relative to the actuating lever 29 is such that these parts may be conveniently grasped by the forefinger and thumb respectively. Due to the position and shape of the actuating lever and segment, a great deal of pressure may be exerted on the scraper.

In cleaning the disher, the scraper, spindle and pinion may be swung from operative position by merely removing the trunnion 23 from the hole 24. The scraper can then be pulled outwardly and the assembly pivoted about the axis of the bearing 20. The scraper and spindle can not be removed from the disher since the pinion 27 is secured at the end of the spindle and since the bearings 20 is riveted to the frame. A portion 44 of the pinion 27 is blank, as shown in Fig. 4, to prevent incorrect re-enmeshing of the pinion with the segment 28. When the pinion has been disengaged from its operating segment, as when cleaning the scraper, the uncoiling of the spring 30 is prevented by the engagement of the stop 39 with the side of the frame 13.

In assembling the actuating lever and segment on the pin 31, the segment 28 is positioned over the bracket 17, and the housing 34 together with the pin 31 and spring 35 are placed over the sleeve 30 which is integral with or secured to the segment 28. After this has been done, it is merely necessary to rotate the housing relative to the bracket until the desired tension has been put on the spring 35 and then tighten the nut 33. The end of the spring 37 will read-

ily fall into the notch 38 formed in the sleeve 30 and will be held therein by the end of the housing 34. The other end of this spring will also be held in its notch in the housing 34 by the segment 28 after the pin 31 has been secured to the bracket 17 by the nut 33.

In using the disher the handle 14 is grasped so that the index finger rests upon the pin 43, and the side of this finger lies adjacent and engages the plate 41 so that considerable pressure may be exerted in the scooping operation. In dishing the cream, the finger rest pin 43 permits the operator to utilize the strength of his thumb and finger in the most efficient manner. Due to this arrangement, a long stroke of the thumb is possible, making the thumb pressure necessary to operate the scraper much less than required in ice cream dishers now in use. The position of the finger rest may be adjusted to suit the user by partially unscrewing the handle 14, it being apparent that it is merely clamped between the washer 16 and the end of the handle.

As above pointed out, the scraper may be removed from the bowl without dislocating the actuating mechanism. Since the bearing 20 is pivotally mounted between the sides of the frame, the bearing is self-aligning with reference to the spindle.

While the form of mechanism herein shown and described is admirably adapted to fulfill the objects primarily stated, it is to be understood that it is not intended to confine the invention to the one form of embodiment herein disclosed, for it is susceptible of embodiment in various forms, all coming within the scope of the claims which follow:

1. In an ice cream disher, the combination of a handle, a U-shaped frame secured thereto, a bowl secured to said frame, a scraper in said bowl having a trunnion; a trunnion bearing in said bowl, a spindle secured to said scraper, a socket bearing for the end of said spindle adjacent said handle, and a bearing for the other end of said spindle, said latter bearing being mounted in said frame, for rotation about an axis at an angle to said spindle.

2. In an ice cream disher, the combination of a handle, a frame, a bowl secured to said frame, a scraper in said bowl, a spindle fixed to said scraper and rotatable in said frame, a movable bearing in said frame adjacent said bowl for said spindle, and means for securing said handle to said frame comprising a screw extending through said frame and threaded in said handle, said screw being provided with an axial socket bearing for said spindle.

3. In an ice cream disher, the combination of a bowl, a handle, a U-shaped frame having its ends joined to said bowl, means

for attaching its cross portion to said handle, a scraper pivoted in said bowl, a movable bearing mounted between the sides of said frame adjacent their ends, actuating means, and a spindle operable thereby, said spindle being adapted to oscillate said scraper and being pivotally mounted in said movable bearing and in a socket bearing formed in said attaching means.

4. In an ice cream disher, the combination of a bowl, a supporting frame for said bowl, a handle on said frame, a scraper in said bowl, means to oscillate said scraper, and a finger rest secured between said frame and handle having a rearwardly projecting pin adjacent said handle, located to permit the fingers to resist reaction of the thumb in oscillating said scraper.

5. In an ice cream disher, the combination of a handle, with a frame comprising an end portion, flat legs extending at substantially right angles to said end portion, curved flanges on the ends of said legs, a hemispherical bowl secured to said flanges, a flat plate between said handle and frame and adapted to provide a seating surface for the side of the hand, a finger rest secured to said plate screw means through said end portion and plate to secure the same to said handle, said screw means having a cupped head to journal a spindle, a spindle having a scraper rotatably supported in said frame and bowl, and means for operating said scraper.

6. In an ice cream disher, the combination of a handle, a frame, a bowl secured to said frame, a scraper in said bowl, a spindle fixed to said scraper and rotatable in said frame, a bearing for said spindle, said bearing being mounted in said frame for rotation at right angles to said spindle, said bowl having an aperture to journal one end of said scraper, means for securing said handle to said frame comprising a screw extending through said frame and threaded in said handle, said screw being provided with a socket in its head forming a bearing for said spindle, and means for rotating said spindle and scraper.

7. In an ice cream disher, the combination of a handle, a frame, a bowl secured to said frame, a scraper in said bowl, a spindle fixed to said scraper and rotatable in said frame, a bearing for said spindle, said bearing being mounted in said frame for rotation at right angles to said spindle, said bowl having an aperture to journal one end of said scraper, means for securing said handle to said frame comprising a screw extending through said frame and threaded in said handle, said screw being provided with a socket in its head forming a bearing for said spindle, a flat plate clamped between said frame and handle by said screw and projecting at substantially right angles to said handle to provide a seating surface for

the side of the hand, and means for rotating said spindle and scraper.

8. In an ice cream disher, the combination of a handle, a frame, a bowl secured to said frame, a scraper in said bowl, a spindle fixed to said scraper and rotatable in said frame, a bearing for said spindle, said bearing being mounted in said frame for rotation at right angles to said spindle, said bowl having an aperture to journal one end of said scraper, means for securing said handle to said frame comprising a screw extending through said frame and threaded in said handle, said screw being provided with a socket in its head forming a bearing for said spindle, a flat plate clamped between said frame and handle by said screw and projecting at substantially right angles to said handle to provide a seating surface for the side of the hand, and a second plate clamped between the head of said screw and said frame, a pinion on said spindle, a toothed sector rotatably mounted on said second plate to mesh with said pinion and a thumb piece on said sector to actuate said scraper.

9. In an ice cream disher, the combination of a handle, a frame, a bowl secured to said frame, a scraper in said bowl, a spindle fixed to said scraper and rotatable in said frame, a bearing for said spindle, said bearing being mounted in said frame for rotation at right angles to said spindle, said bowl having an aperture to journal one end of said scraper, means for securing said handle to said frame comprising a screw extending through said frame and threaded in said handle, said screw being provided with a socket in its head forming a bearing for said spindle, a flat plate clamped between said frame and handle by said screw and projecting at substantially right angles to said handle to provide a seating surface for the side of the hand, and a second plate clamped between the head of said screw and said frame, a pinion on said spindle, a toothed sector rotatably mounted on said second plate to mesh with said pinion, a thumb piece on said sector to actuate said scraper, and a rearwardly projecting pin on said first-mentioned flat plate and located on the opposite side of said handle from said thumb piece.

10. In an ice cream disher, the combination of a handle, a frame secured to said handle, said frame having a pair of legs, a bowl fixed to said frame, said bowl having an aperture opposite said frame, a resilient scraper having one end rotatably mounted in said aperture, a spindle secured to the other end of said scraper, a bearing for the end of said spindle supported by said handle, and a second bearing for said spindle rotatably supported between said legs at an angle to the axis of rotation of said spindle.

11. In an ice cream disher, the combination of a handle, a frame secured to said handle, said frame having a pair of legs, a bowl fixed to said frame, said bowl having an aperture opposite said frame, a resilient scraper having one end rotatably mounted in said aperture, a spindle secured to the other end of said scraper; a bearing for the end of said spindle supported by said handle, a second bearing for said spindle rotatably supported between said legs at an angle to the axis of rotation of said spindle, a pinion on said spindle, a bracket secured between said legs adjacent said pinion, a toothed sector rotatably mounted on said bracket and meshing with said pinion, a sleeve supported by said sector having a slot in its end, a cap for said sleeve having an axial bolt fixed therein to journal said sector, and a spring tensioned between said cap and sleeve and enclosed by said cap.
12. In an ice cream disher, a bowl, a scraper rotatably supported in said bowl, a frame comprising an end portion and spaced side portions, a handle secured to said end portion by screw, a bearing in said screw, a movable bearing mounted between said side portions adjacent said bowl, a spindle for said scraper mounted in said bearing, a plate secured to said handle by said screw, and a finger rest on said plate.
13. In an ice cream disher, a bowl, a scraper rotatably supported in said bowl, a frame comprising an end portion and spaced side portions, a handle secured to said end portion by a screw extending inwardly into said handle, said screw being fixedly secured to said frame end portion, a bearing in said screw, a movable bearing mounted between said side portions adjacent said bowl, a spindle for said scraper mounted in said bearings, a plate secured to said handle by said screw, and a finger rest mounted at an extremity of said plate and extending substantially parallel to said handle.
14. In a device of the class described, a bowl, a frame, a scraper rotatably supported in said bowl, a spindle secured to said scraper and rotatable relative to said frame, a movable bearing in said frame adjacent said bowl for said spindle, a handle, and means for securing said frame to said handle comprising a screw riveted to said frame, the head of said screw having a socket bearing for the end of said spindle formed therein.
15. In an ice cream disher, the combination of a bowl, a supporting frame for said bowl, a handle on said frame, a spindle having one end secured to a scraper in said bowl, a pinion fixed at the other end of said spindle, a movable bearing in said frame adjacent said bowl for said spindle, a segment engaging said pinion mounted for reciprocation in a plane perpendicular to the

axis of said spindle, a spring for actuating said segment in one direction and stops on said segment adapted to abut against said frame to limit the movement of said segment.

16. In a device of the class described, a supporting frame, a handle supported on said frame by screw means, a flat plate between said handle and frame adapted to provide a seating surface for the side of the hand, an actuating lever having a thumb piece, a frame, a bowl secured thereto, a scraper in said bowl operated by said actuating lever, and means on said flat plate to permit the fingers to resist reaction of the thumb on the said thumb piece.

17. In an ice cream disher, a handle comprising a hand grip, a flat plate at one end thereof extending transversely thereto to prevent longitudinal sliding of the hand on said grip, an actuating lever having a thumb piece, a frame, a bowl secured thereto, a scraper in said bowl operated by said actuating lever, and means on said flat plate to permit the fingers to resist reaction of the thumb on the said thumb piece.

18. In an ice cream disher, the combination of a bowl, a frame secured to said bowl, a handle on said frame, a scraper pivoted in said bowl, means to oscillate said scraper including a thumb piece, a finger rest fixed relative to said handle and positioned adjacent one end thereof, and a projection on said finger rest adapted to engage the fingers of the operator to permit the operator to press said thumb piece and said finger rest between the thumb and fingers.

19. In an ice cream disher, the combination of a scoop with a supporting frame, including a handle, a scraper rotatable in said scoop, a spindle for supporting said scraper, and a bearing carried by said frame for rotatably supporting said spindle, said bearing being rotatably mounted relative to said frame on an axis transverse to the axis of said spindle, and said spindle being slidably mounted in said bearing.

In witness whereof, I hereunto subscribe my name this 29th day of April, 1926.
